UNITED STATES PATENT OFFICE

171,857

PAPOOSE DOLL

Robert L. Oyler, Long Beach, Calif.

Application September 14, 1953, Serial No. 26,793

Term of patent 14 years

(Cl. D34—4)

To all whom it may concern:

Be it known that I, Robert L. Oyler, have invented a new, original and ornamental Design for a Papoose Doll, of which the following is a specification, reference being had to the accompanying drawing, forming a part hereof.

Figure 1 is a front elevational view of a papoose doll, showing my new design;

Figure 2 is a side elevational view thereof; and,
Figure 3 is a top plan view thereof.

I claim:

The ornamental design for a papoose doll, substantially as shown.

ROBERT L. OYLER.
